UNITED STATES PATENT OFFICE.

FRANK ELVIN PIPER, OF RED DEER, CANADA.

BRICK-EDGING MACHINE.

No. 805,152.

Specification of Letters Patent.

Patented Nov. 21, 1905.

Application filed March 25, 1905. Serial No. 251,935.

To all whom it may concern:

Be it known that I, FRANK ELVIN PIPER, a subject of the King of Great Britain, residing at Red Deer, district of Alberta, North-West Territories, Canada, have invented certain new and useful Improvements in Brick - Edging Machines; and I do hereby declare that the following is a full, clear, and exact description of the invention, such as will enable others skilled in the art to which it appertains to make and use the same.

This invention relates to new and useful machines adapted to be used in edging bricks; and it consists in certain features of novelty in the construction and operation thereof, all as hereinafter more fully described, and specifically pointed out in the claims.

The object of the invention is to provide a machine for the purpose stated which will be practically automatic in its operation and which is so constructed that bricks may be deposited upon pallets in a swinging pallet-frame, said bricks being deposited upon their sides, and by means of the mechanism hereinafter described said bricks are automatically deposited upon their edges upon a table provided for that purpose.

The machine comprises in its operative parts a movable pallet-frame pivotally mounted on a fixed frame, so as to be capable of both lateral and vertical movement upon relatively fixed pivots, and includes in its construction adjusting means whereby the machine is placed in operation in such relation to the adjustable driving mechanism that greater or less speed of operation may result, according to the requirements.

The machine also comprises other features of novelty relating to the construction and operation thereof, all as hereinafter more fully described.

Referring to the annexed drawings, in which similar numerals of reference indicate corresponding parts in all the views, Figure 1 is a plan view of the machine. Fig. 2 is a side elevational view thereof. Fig. 3 is a front elevational view. Fig. 4 is a fragmentary side elevational view looking toward the side opposite that shown in Fig. 2. Fig. 5 is a sectional view illustrating the clutch mechanism hereinafter referred to. Fig. 6 is a detail of a portion of said clutch mechanism, being approximately a sectional view on line 6-6 of Fig. 5. Fig. 7 is a longitudinal sectional view taken on line 7-7 of Fig. 1 looking in the direction indicated by the arrow.

Fig. 8 is a view showing a portion of the supporting-frame with the pallet-frame and its immediate connections shown in different positions for the purpose of better illustrating the operation of the machine. Fig. 9 is a sectional view taken on line 9-9 of Fig. 1 looking in the direction indicated by the arrow.

Referring to the parts, 1 is a relatively fixed frame hereinafter referred to as a "supporting-frame," upon which the operative mechanism is carried. Rising from the supporting-frame 1 are vertically-disposed brackets 2, which are pivotally connected with said supporting-frame, and said brackets are provided with the cam-shaped slots 3, which are disposed approximately in the arc of a circle struck from the center of the transversely-extending shaft 4, upon which the pallet-frame hereinafter described is supported. The brackets 2 serve as supporting means for said shaft 4, and bearings 5 6 on said supporting-frame 1 and connected with said fixed frame 1 and with said brackets 2 serve as means for pivotally mounting the pallet-frame on the shaft 7, the pallet-frame being so mounted as to permit it to be tilted laterally, as shown by the dotted lines in Fig. 3, for loading and also capable of swinging movement, as shown in Fig. 8, for the purpose hereinafter described. Said brackets 2 are formed as flanges rising vertically from the bed-plate 2^a, with which said bearing 6 is connected.

The pallet-frame 8 is slotted longitudinally, as shown, said slots 8^a serving as bearings for the crank-pins 9, by means of which the position of the slidable pallets 10 are regulated, while the crank-pins 9^a serve as means for rocking the relatively fixed pallet 10^a. Extending longitudinally of the pallet-frame is the link 11, which is connected, by means of the bell-crank 12, with the longitudinally-slotted link 13, and the crank-pins 9 9^a, which serve as pintles for the said pallets 10 10^a, enter the slots 14^a of said link 13 and are guided thereby. Connecting the link 11 with the bell-crank lever 14 is a link or rod 15, whereby movement of the links 11 and 13 are controlled by said bell-crank lever 14, which latter is pivoted at 15^a in the pallet-frame 8 and is provided with the pin 16, adapted to travel in said cam-shaped groove 3 in the bracket 2. Thus when said pallet-frame is rocked upon its supporting-shaft 4 the pin 16 travels in the cam-groove 3, thereby rocking the bell-crank lever 14, and through the link 15, pivotally connected with the link 11, and

the bell-crank levers 12, pivotally connected to the link 13, the crank-pins 9 9^a of the pallets 10 10^a are rocked, so that, regardless of the elevation of the free end of the pallet-frame, said pallets are always held with their bottoms in a horizontal position until said pallet-frame reaches its maximum elevation, as shown by the central dotted portion of Fig. 8, after which the continued movement 10 of said pallet-frame and the appurtenant connections described turns said pallets to the position shown in dotted lines at the left of Fig. 8, wherein the bottom plates thereof are turned to a vertical position, thereby placing 15 the bricks upon their edges, it being understood that the bricks are placed upon their flat sides in the first instance, and through the turning of the pallets the bricks are carried to a position where they will rest upon their 20 longitudinal edges. Coöoperating with the pallet-frame and said pallets is a yoke 18, which is pivotally supported upon the shaft 19, so as to be rockable thereupon, and extending from said yoke 18 are three arms 20, 25 21, and 22, through which extend the pintles 9^b of the slidable pallet-frames 10.

In Fig. 7, counting from the bracket 2, it will be noted that the second pallet-frame 10^a is carried on a pintle 9^c and said pallet, though 30 rockable on said pintle, is not slidable in the pallet-frame.

By reason of the eccentric relation of the pintle connection of the arms 20, 21, and 22 to the shaft 19 it will be observed that as the 35 pallet-frame is carried upwardly said arms will act as follows: The arm 20 will carry the pallet connected therewith in a direction toward the free end of the pallet-frame, while the arms 21 and 22 will carry the pallet located near the free end of said pallet-frame 40 toward the pallet 10^a, held centrally thereof, thereby bringing said pallets nearer together and causing the bricks to be deposited more closely together than would otherwise result.

Coöoperating with the pallet-frame described 45 is a table 24, which is carried by the frame 25 and is removably mounted upon said frame, the frame having the laterally-extending arms 26 for supporting the table. The frame 50 25 is mounted upon the rockable shaft 27, held in the bearing 28, extending from the frame 1. Integral with the frame 25 is an extension 29, extending beyond said shaft 27, and pivotally connected with said extension 55 29 is a link 30, which link is pivotally connected at its opposite end with the link 31, which in turn is rigidly connected to and mounted upon the transversely-extending stub-shaft 32, held in suitable bearings on the 60 frame 1. Rigidly connected with said stub-shaft 32 and extending downwardly therefrom is a second link 33, which is provided at its lower end with a pin or roller 34, adapted to travel in the cam groove or channel 35 in the 65 cam-wheel 36, so that at the proper time the

links 31 33 and stub-shaft 32, through the medium of said cam 36 and the connecting-link 30, will rock the frame 25 for the purpose hereinafter referred to. Mounted on said shaft 27 is a segment 37, which is rigidly 70 connected therewith, and meshing with the segment 37 is a segment 38, carried by the segment-frame 39, which segment-frame is mounted upon the stub-shaft 40, as best shown in Fig. 2. Connecting the cam 36 with the 75 segment-frame 39 is a pitman 41.

Rigidly connected with the shaft 27 is a crank-arm 42, having the laterally-extending cranked portion 43 and inner longitudinally-extending portion 44, as best shown in the 80 plan view, Fig. 1. A bearing 45 is provided, as best shown in Fig. 7, for the crank-arm 42 44, said bearing being connected with the downwardly-extending portion 46 of the pallet-frame 8, and it will be evident that 85 when the shaft 27 is rocked in the proper direction said pallet-frame will be raised by means of the crank-arm 42 44.

The cam 36 before referred to is carried upon the shaft 48, which shaft has mounted 90 thereupon the driving mechanism hereinafter described, and the shaft 48 through said driving mechanism is driven from the power-shaft 49.

In a machine of this character it is desirable 95 that its operation shall be as nearly as possible automatic, and to that end there is provided an adjustable time-regulator which may be adjusted so that the driving mechanism will become effective to raise the pallet-frame and its 100 appurtenant connections either very quickly after the bricks have been deposited upon the pallets or after the lapse of a short period of time, as may be desired, and to that end means are provided as follows: Referring to Figs. 5 105 and 6, it will be noted that there is mounted upon the cam-shaft 48 a gear-wheel 50, having external and internal teeth 51 and 52, said wheel 50 being loosely mounted upon said shaft 48. In convenient juxtaposition to the wheel 50 is 110 a band-wheel 53, having any desired number of spokes, though shown in Fig. 6 as provided with three spokes 54, the said wheel 53 being held by means of the key 55 rigid to the shaft 48, so as to be rotatable therewith. Next beyond the wheel 53 is a sleeve 56, which is also loosely mounted upon the shaft 48. Slidable longitudinally of the sleeve 56 is a collar 57, having a circumferential groove or channel 58 therein, in which is mounted the yoke 59. (Shown in Figs. 3 and 5.) Extending from the sleeve 56 and rotatable therewith is a ratchet-frame 60, having the ratchet-teeth 61 formed in the cam-shaped rack or segment 62 thereof. Mounted in the member 60 is a radially-slidable pin 63, which is connected with the pawl-arm 64, which pawl-arm or pawl is adapted to engage with the inner teeth 52 of the wheel 50, as hereinafter described. Connecting the collar 57 with the pawl-arm 64 is 125 130

a link 65, which is pivotally connected to said collar and said pawl and is so arranged that when the collar 57 is carried in a direction away from the wheel 50 the pawl 64 will be carried away from the teeth 52 of said wheel 50 and disengage therefrom; but when it is desired to start the machine in operation the collar 57 is carried in a direction toward the wheel 50, whereupon the pawl 64 will engage the inner teeth 52, thereby causing the sleeve 56 to rotate with the wheel 50 until the pawl 64 comes into contact with one of the spokes 54 of the band-wheel 53, whereupon the shaft 48, carrying the cam 36, will be rotated, and for each complete rotation of said cam 36 the pallet-frame will be lifted from the position shown in Fig. 2 to the position shown in dotted lines at the left of Fig. 8, thereby turning the bricks which may have been placed upon the pallets from their flat sides to their edges. It will be understood that the driving-shaft 49 carries the driving-pulley 70 and the pinion 71, which meshes with the teeth 51 of the gear-wheel 50, and the gear-wheel 50 is in constant rotation while the machine is in service, depending upon the clutch mechanism disclosed in Figs. 5 and 6 to operate the cam-shaft 48, which then becomes the actuating-shaft of the machine. The cam-shaped segmental rack 62 is loosely mounted upon the sleeve 56 and, as will be noted in Fig. 4, coöperates with the pawl 72, which pawl serves to normally sustain said rack in any desired position. The pawl 72 is provided with the counterbalanced extension 73, beyond the pivot 74 thereof, and said counterbalance is adapted to rest upon the extension 75 of the arm 76. Perforations are provided in the segment 77, and by means of a pin 78 the arm 75 76 may be swung upon its pivot in the bracket 79, so that the portion 75 may raise and lower the counterbalance portion of the pawl 72, and as the segmental rack 62 is eccentrically journaled upon the shaft 48 it is evident that the normal position of said segmental rack is determined by said pawl 72. Thus if it is desired to start the operation of the machine quickly upon turning the pallet-frame from the dotted position shown in Fig. 3 to the full position then the rack 72 is placed so that the pawl 64 will be near to one of the spokes 54; but if a longer period of time is required the pawl 72 and said rack 61 are so adjusted that the pawl 64 will rest normally at a position farther away from said spoke 54, and a longer time will be required for said pawl 64 to contact with the contiguous spoke 54 of the wheel 53.

Mounted upon the wheel 53 is a pawl 80, influenced by the spring 81 to engage the pawl 64, so that when the parts are engaged, as just described, the segmental rack 62 cannot become accidentally disengaged and fall back by gravity after the teeth thereof have passed beyond range of the pawl 72.

65 Coöperating with the clutch mechanism just

described is a lever 83, which is mounted upon and rigidly connected with the shaft 84, to which is rigidly connected the yoke 59 before referred to. Held within the bifurcated end 85 of the lever 83 is a pin 86, projecting laterally from the rockable member 87, which is carried upon the shaft 7, so that as the pallet-frame is rocked laterally upon said shaft 7 the members 59, 83, and 87 will be thrown as follows: When said pallet-frame is thrown laterally to the position indicated by the dotted lines in Fig. 3, the yoke 59 will carry the collar 57 away from the wheel 53, thereby disengaging the pawl 64 from the teeth 52 of the gear-wheel 50; but when the pallet-frame is thrown to the position shown in full lines in said Fig. 3 and as shown in Fig. 1 in the plan view the members 59, 83, and 87 will be thrown to the position indicated in full lines in Fig. 3, thereby shifting the collar 57 nearer to the gear-wheel 50, thereby causing the pawl 64 to engage with the inner teeth thereof, with the result heretofore described.

In addition to the clutch mechanism hereinbefore described the driving-pulley 70 is provided with a clutch 70^a, controlled by means of the rod 70^b and lever 70^c, so that, if desired, said pulley 70 may rotate idly upon its shaft.

Instead of the band-wheel 53 a single spoke, 95 as 54, may extend from a hub keyed on the shaft 48 with the same result in operation.

In a machine which has been built the sleeve 56 and collar 57 are formed of a single casting, which slides longitudinally of the shaft 100 48, carrying a pawl corresponding to the pawl 64 into engagement with teeth on the side of the wheel 50, and it will be evident that such construction may be substituted for that shown in Fig. 5 in some cases with beneficial results. 105

A weighted arm (not shown) may be used to balance the parts 24, 25, and 26, if desired, and it is evident that weights may be substituted for the spring 30^a with good results.

It is to be noted that when the pallet-frame is tilted to the position shown in dotted lines in Fig. 3 the bricks may be emptied from the mold onto the pallets 10 and 10^a on their flat sides in the first instance, thus giving the operator ample time to deposit the bricks before the pallet-frame is righted and lifted as described.

On the arms 26 are fixed clips 26^a and rockable clips 26^b, the latter of which are provided with the springs 26^c, adapted to normally hold them in engagement with the table 24; but when the pallet-frame occupies the position shown in dotted lines at the left of Fig. 8 the rockable clips strike the arm 25^a, thereby releasing the table 24, so that it may be removed. 125

It will be evident from the foregoing that bricks may be deposited on the pallets from the molds, the bricks resting upon their flat faces, after which the pallet-frame may be rocked to the position shown in Fig. 1, where- 130

upon if power is applied to the shaft 49 the machine will automatically turn said bricks and deposit them on their longitudinal edges upon the removable table 24, which may be 5 then removed from the frame 25 26 and carried to the yard or kilns for drying.

Extending from the bearing 28 to the crank-arm comprising the members 31, 32, and 33 is a tension-spring 30^a, which tends to hold 10 the pin or roller 34 in the cam-groove 35.

While I have shown in the accompanying drawings the preferred form of my invention, it will be understood that I do not limit myself to the precise form shown, for many of 15 the details may be changed in form or position without affecting the operativeness or utility of my invention, and I therefore reserve the right to make all such modifications as are included within the scope of the following 20 claims or of mechanical equivalents to the structures set forth.

Having described my invention, what I claim, and desire to secure by Letters Patent, is—

25 1. In a brick-edging machine, a laterally and vertically swinging pallet-frame.

2. In a brick-edging machine, a laterally and vertically swinging pallet-frame, and means for swinging the same vertically.

30 3. In a brick-edging machine, a laterally and vertically swinging pallet-frame, pallets slidably mounted therein, and means for sliding some of said pallets.

4. In a brick-edging machine, a laterally and vertically swinging pallet-frame, pallets pivotally mounted in said frame, and means for rocking said pallets during vertical movement of said frame.

5. In a brick-edging machine, a laterally and vertically swinging pallet-frame, pallets slidably mounted therein, and means for sliding some of said pallets, in combination with a table-supporting frame rockably mounted in juxtaposition to said pallet-frame.

45 6. In a brick-edging machine, a laterally and vertically swinging pallet-frame, pallets pivotally mounted in said frame, and means for rocking said pallets during vertical movement of said frame, in combination with a table-supporting frame rockably mounted in juxtaposition to said pallet-frame.

7. In a brick-edging machine, a laterally and vertically swinging pallet-frame, in combination with a rockable rack-frame, a rack 55 connected with said pallet-frame meshing with said rack-frame, and means for rocking the rack-frame.

60 8. In a brick-edging machine, a laterally and vertically swinging pallet-frame, pallets slidably mounted therein, and means for sliding some of said pallets, in combination with a rockable rack-frame, a rack connected with said pallet-frame meshing with said rack-frame, and means for rocking the rack-frame.

65 9. In a brick-edging machine, a relatively

fixed supporting-frame, a movable frame pivotally mounted thereon, pallets pivotally mounted in said movable frame, and means for rocking said movable frame.

10. In a brick-edging machine, a relatively 70 fixed supporting-frame, a laterally and vertically movable frame pivotally mounted thereon, pallets pivotally mounted in said movable frame, and means for rocking said movable frame.

11. In a brick-edging machine, a supporting-frame, a laterally and vertically swinging pallet-frame, a crank-shaft rockably mounted in said supporting-frame, a segment operatively connected with said crank-shaft, a segment-frame carrying a segment in mesh with the first-mentioned segment, a rotatable cam, and a pitman connecting said rotatable cam with said segment-frame.

12. In a brick-edging machine, a laterally 85 and vertically swinging pallet-frame, means for rocking said pallets during vertical movement of said frame, and means for sliding said pallets longitudinally of said pallet-frame.

13. In a brick-edging machine, a vertically- 90 swinging pallet-frame, a supporting-frame therefor, a stub-shaft extending laterally from the supporting-frame, a crank-arm rigidly connected with said stub-shaft and extending below the pallet-frame, and means for rocking said stub-shaft.

14. In a brick-edging machine, a vertically- 95 swinging pallet-frame, pallets rockable and slidably mounted therein, and means for rocking and sliding said pallets in said frame.

15. In a brick-edging machine, a vertically- 100 swinging pallet-frame, pallets slidably and rockably mounted therein, means for rocking and means for sliding said pallets, and means for swinging said pallet-frame vertically, in combination with a table-frame rockably mounted in juxtaposition to said pallet-frame, and means for swinging said table-frame.

16. In a brick-edging machine, a vertically- 110 swinging pallet-frame, a crank-arm journaled to said pallet-frame, a rockable stub-shaft on which said crank-arm is rigidly mounted, and means for rocking said stub-shaft.

17. In a brick-edging machine, a vertically- 115 swinging pallet-frame, pallets slidably mounted in said frame, supporting-brackets, an eccentric yoke mounted in one of said brackets, and arms extending from said yoke to and connected with pallets mounted in said pallet-frame.

18. In a brick-edging machine, a laterally and vertically swinging pallet-frame, in combination with actuating means therefor comprising a rotatable cam, crank-arms actuated thereby, a link pivotally connected with one 125 of said crank-arms, a rockable table-frame connected with said link, and means for actuating said cam.

19. In a brick-edging machine, a vertically- 130 swinging pallet-frame and a vertically-swing-

ing table-frame, pallets rockably and slidably mounted in said pallet-frame, and means for swinging said table-frame and said pallet-frame.

5 20. In a brick-edging machine, a vertically and laterally swinging pallet-frame, in combination with a clutch comprising a gear-wheel loosely mounted on its shaft, a sleeve in convenient proximity to said gear-wheel, 10 a pawl carried by said sleeve adapted to engage the teeth of said gear-wheel, a collar slidable upon said sleeve, a link connecting said collar with said pawl, and a spoked wheel locked to the shaft on which said gear-wheel 15 is mounted.

21. In a brick-edging machine, a supporting-frame, a vertically-swinging pallet-frame mounted thereon, a stub-shaft extending laterally from said frame, a crank-arm rigidly 20 mounted on said stub-shaft and connected with said pallet-frame, a segment rigidly mounted on said stub-shaft, a second segment in engagement therewith, a segment-frame carrying said second segment, rotatable actuating means, and a pitman connecting said 25 rotatable actuating means with said segment-frame.

22. In a brick-edging machine, a laterally and vertically swinging pallet-frame, a continuously-driven power-shaft, a second shaft 30 in proximity therewith, a pinion on the power-shaft, a loosely-mounted gear on the second shaft, a clutch mechanism automatically operated by swinging said pallet-frame laterally to actuate said second shaft, and means 35 on said second shaft adapted to swing said pallet-frame vertically.

23. In a brick-edging machine, a laterally and vertically swinging pallet-frame, in combination with an automatically - operated 40 clutch adapted to swing said frame vertically.

24. In a brick-edging machine, a laterally and vertically swinging pallet-frame, in combination with an automatically - operated clutch adapted to swing said frame vertically, 45 in combination with adjustable means for timing the action of said clutch.

In witness whereof I have hereunto set my hand in the presence of two witnesses.

FRANK ELVIN PIPER.
